(57) **CLAIM**

The ornamental design for a strap for athletic training as shown and described.

DESCRIPTION

FIG. 1 is a perspective view of a strap for athletic training; FIG. 2 is a front elevation view thereof;

FIG. 3 is a rear elevation view thereof, identical to the front elevation view;

FIG. 4 is a first side elevation view thereof; and,

FIG. 5 is a second side elevation view thereof, opposite and identical to the first side elevation view.

Top and bottom plan views are not provided because they would not contain visual information or surface ornamentation relevant to the design.
